UNITED STATES PATENT OFFICE.

ALBERT G. ELVIN, OF EAST ORANGE, NEW JERSEY.

FLUID-PRESSURE MOTOR.

1,030,062.

Specification of Letters Patent. Patented June 18, 1912.

Application filed March 10, 1910. Serial No. 548,857.

To all whom it may concern:

Be it known that I, ALBERT G. ELVIN, of East Orange, in the county of Essex and State of New Jersey, have invented a certain new and useful Improvement in Fluid-Pressure Motors for Fire-Box Doors, of which improvement the following is a specification.

My present invention relates to pneumatic door operating mechanism of the general class or type of that set forth in an application for Letters Patent filed by me February 5, 1907, Ser. No. 355,877, and its object is to provide an appliance of such type which shall attain the advantages of that of said application, and embody the further advantages of effecting both the opening and closure of the door by fluid pressure and of cushioning the movements of the door in both directions.

The improvement claimed is hereinafter fully set forth.

In the accompanying drawings: Figure 1 is a front view of a firebox door operating appliance illustrating an application of my invention, with the operating cylinder thereof in longitudinal central section; Fig. 2, a plan or top view, partly in section, of the operating cylinder; Fig. 3, a plan view, on an enlarged scale, of the operating cylinder; Fig. 4, a vertical longitudinal section through the left hand portion of the operating cylinder on the line *a b b* of Fig. 3; Fig. 5, a transverse section through the operating cylinder, on the line *c c* of Fig. 3; Fig. 6, a partial vertical longitudinal section through the same, on the line *a a* of Fig. 3; and, Fig. 7, a vertical section through the firing opening and one of the door sections.

My invention is herein exemplified in connection with a fire door appliance comprehending two door leaves or sections, 9, 9^a, which are fitted to slide horizontally toward and from each other in guides, 3, on a door frame, and to cover and uncover, as the case may be, a firing opening, 2, in a firebox or furnace, 1, to which the door frame is connected. The door sections are moved from and toward each other, to open and close, respectively, the firing opening, by means of levers, 12, 12^a, pivoted by pins or bolts, 13, to a downward extension of the operating cylinder hereinafter described, the lower and longer arms of said levers being coupled to the door sections. Inter-

meshing segment gears, 17, 17^a, are formed on the levers, concentric with their pivots, 13, and by the oscillation of said segment gears about their axes, the door sections will be moved from or toward each other, as the same may be. A hand lever, 18, is pivoted to the bottom guide of the door frame, and is provided with a longitudinal slot, 18^a, engaging a pin, 18^b, fixed to the door section, 9, for the purpose of operating the door sections manually, when desired.

In the practice of my invention, as applied in connection with a door mechanism of the type above described, a fluid pressure operating cylinder, 25, is bolted to the top of the door frame, 3. The cylinder, 25, is cut away on its lower side, so as to allow the segment gears, 17, 17^a, to project into it, and is closed at its ends by heads 26, 27. The bore of the cylinder, 25, is made of two different diameters, being greater at, and for some distance from, one of its ends, than for the remainder of its length.

A piston, 28, is fitted in the cylinder, 25, said piston being, for the major portion of its length, of such diameter as to fit neatly in the smaller bore of the cylinder, and having a head at one end, similarly fitting the larger bore, suitable packing rings, 29, being provided in the head and at the opposite end of the piston, to prevent leakage of fluid. The piston, 28, is recessed on its lower side, to admit the segment gears, 17, 17^a, and a longitudinal rack or set of teeth, 30, meshing with the gear, 17, is formed in the recess of the piston. Movement to the right or to the left, as desired, is imparted to the piston by fluid pressure, as herein-after described, and it will be seen that such movement will, through the segment gears and their connections, move the door sections apart or bring them together, as the case may be.

The supply and exhaust of motive fluid to and from the opposite ends of the piston, 28, to effect the opening and closing movements of the door sections, are effected by the following means. A valve chamber, 34, which is closed at its top by a removable plug, 34^a, is formed in the head, 26, of the operating cylinder, 25, said chamber communicating, at its bottom, with a cylindrical bore which extends through the head and has a valve seat at its top for the reception of a door opening supply and exhaust valve, 33, which seats downwardly,

and is fixed upon a cylindrical stem, 35, fitting truly in the cylindrical bore and extending for a short distance below the lower end thereof. A valve chamber, 54, which is closed at its bottom by a removable plug, 54^a, is formed in the opposite head, 27, of the cylinder, said chamber communicating, at its top, with a cylindrical bore which extends through the head, but 5
10 is closed to the atmosphere by a removable plug, 54^b. A valve seat is formed at the bottom of said cylindrical bore, for the reception of a door closing supply and exhaust valve, 53, which seats upwardly and 15 is fixed upon a cylindrical stem, 55, fitting truly in the cylindrical bore.

A supply pipe, 31, leads from any suitable source of fluid pressure supply, as a main reservoir of an air brake system, into a 20 strainer chamber, 31^a, located on one side of the operating cylinder, 25, which chamber may be loosely packed with any material suitable to prevent ingress of dirt and other foreign matter. The supply pipe, 31, and strainer chamber, 31^a, communicate by a passage, 31^b, with a supply passage, 43, which extends longitudinally in the wall of the cylinder, 25, from one of its heads to the other. The passage, 43, communicates, 25 at one of its ends, with a passage 44, leading into the valve chamber, 34, and communicates, at its opposite end, with a passage, 45, leading into the valve chamber 54. The cylindrical bore in which the stem of the 30 valve, 33, is fitted, communicates with the adjoining end of the cylinder, 25, by a port, 46, and this cylindrical bore communicates with the atmosphere by an exhaust port, 48, located at a lower level than the port, 46. The area available for discharge of fluid through the exhaust port, 48, may be varied, as desired, by a regulating valve, 51, formed on the end of an adjusting screw, 52, engaging a thread in the cylinder head, 26. The cylindrical bore in which the stem of the valve, 53, is fitted, communicates with the adjoining end of the cylinder, 25, by a port, 46^a, and communicates with the atmosphere by an exhaust port, 48^a, located 35 at a higher level than the port, 46^a. The valve stems, 35 and 55, are grooved or peripherally recessed, below and above the valves, 33 and 53, respectively, to effect the opening and closure of ports, as hereinafter 40 described.

A trip rod casing, 56, is formed on the top of the cylinder, 25, to receive and guide a longitudinally sliding trip rod, 57, the casing being provided with a removable 45 cover plate, 56^a, by the detachment of which and of the cylinder head, 27, access may be had to its interior. The trip rod, 57, is recessed or reduced in section for a portion of its length, so as to provide shoulders or 50 bearings, 57^a and 57^b, against one or the

other of which a trip, 58, projecting upwardly from the piston, 28, abuts, in the movements of said piston in either direction, and the end of the trip adjacent to the valve stem, 55, is provided with an inclined bearing face, 57^c, adapted to abut against said valve stem and unseat the valve, 53, as the piston, 28, approaches the terminal of its stroke in the direction of said valve. 70

A rod, 39, having a head, 36, which is in contact with the lower end of the stem, 35, of the valve, 33, is fitted to slide vertically in a guide, 37, on the door frame, and is coupled, at its lower end, to a double armed treadle lever, 41, pivoted to the door frame and carrying a treadle, 42, which normally stands at a level slightly above that of the deck or firing floor of the firebox. By downward pressure of his foot on the treadle, 42, the fireman can, through the lever, 41, and rod, 39, unseat the valve, 33, and upon the release of such pressure the valve will be reseated by the pressure from the supply pipe acting upon it in its chamber, 34. A spring, 39^a, may be applied to return the rod, 39, to normal position. 75

In the operation of the motor, the fireman presses his foot upon the treadle, 42, thereby unseating the valve, 33, and admitting fluid under pressure from the supply pipe, 31, and communicating valve chamber, 34, past the grooved or reduced portion of the valve stem, 35, and through the port, 46; to the left hand end of the operating cylinder, 25, thereby moving the piston, 28, 100 thereof, to the right, and, through the rack, 30, and segment gears, 17 and 17^a, imparting opening movement to the door sections, 9, 9^a. As the piston moves forward, and at a point in its traverse at which it has nearly completed the opening movement of the door sections, the trip, 58, which it carries, strikes the right hand shoulder, 57^b, of the trip rod, 57, thereby moving the latter to the right and unseating the valve, 53, which admits fluid under pressure from its chamber, 54, to the right hand end of the cylinder, 25. This end of the cylinder being of smaller diameter than the left hand or opening end, the pressure admitted will not prevent the complete opening movement of the door sections, but will cushion and prevent them from slamming or opening with a jar or shock. Upon the release of pressure from the treadle, 42, the valve, 33, is seated 110 by the fluid pressure above it, thereby cutting off the supply of fluid to the left hand end of the cylinder, and exhausting the fluid from the left hand side of the piston, 25, through the exhaust port, 48. The pressure from the chamber, 54, acting on the right hand side of the piston will move it to the left, thereby imparting closing movement to the door sections, the trip rod, 57, holding the valve, 53, unseated until the trip, 58, 115 120 125 130

strikes the left hand shoulder, 57^a, of the trip rod, when the latter will be moved to the left, releasing the stem, 55, of the valve, 53, which will be closed by the pressure below it in its chamber, 54, and will cut off the supply of fluid to the right hand end of the cylinder, and open an exhaust therefrom through the exhaust port, 48^a. At this time, the door sections will be nearly closed and 10 their momentum will carry them and the piston to the terminals of movement in closing direction. The regulating valve, 51, is adjusted so as to sufficiently cushion the exhaust from the left hand end of the cylinder to prevent the slamming of the door sections in closing.

The appliance is readily applicable in connection with fireboxes of any of the ordinary constructions, and the working parts 20 involved are comparatively few in number and of such character that they can be substantially made, and are protected from liability to breakage and from damage by the access of dirt. The operation of the 25 door sections is quick, simple, and easy, and the automatic closure of the door sections effects the substantial advantage of compelling single shovel firing, the advantage of which practice, in economizing fuel, perfecting combustion, and reducing firebox and flue repairs, has been universally recognized in railroad service. Another important advantage is afforded in the prevention of serious or fatal injury to the engineer 30 and fireman in the event of a flue bursting or a crown sheet coming down, in which case, an ordinary swinging door would be blown open, allowing the steam and hot water to escape into the cab of the engine.

40 With the mechanically operated door above described, if the door sections should be open and the fireman be firing, the moment he relieves pressure from the treadle the door sections will be automatically closed, 45 thereby preventing the ingress of steam and hot water to the cab, and causing them to be blown down through the grate.

I claim as my invention and desire to secure by Letters Patent:

50 1. The combination of a fluid pressure cylinder having a lateral opening, a differential piston working in said cylinder and having a rack on its side adjacent to said opening in position to engage a gear 55 extending thereinto; an operating valve controlling the supply and exhaust of fluid to and from the larger end of the piston, a valve controlling the supply and exhaust of fluid to and from the smaller end of the piston, and a trip rod adjacent to the cylinder and actuated by the movement of the piston, for opening said last recited valve.

2. The combination of a fluid pressure cylinder, a differential piston working there- 65 in, an operating valve which, when unseat-

ed, admits fluid pressure to the larger end of the piston, and, when seated, exhausts fluid pressure therefrom, and which is continuously subject to fluid supply pressure, means for unseating the operating valve, 70 and a trip rod adjacent to the cylinder and actuated by the movement of the piston, for effecting the supply and exhaust of fluid to and from the smaller end thereof.

3. The combination of a fluid pressure cylinder, a differential piston working therein, an operating valve which, when unseated, admits fluid pressure to the larger end of the piston, and, when seated, exhausts pressure therefrom, and which is continuously subject to fluid supply pressure, means for unseating the operating valve, a valve controlling the supply and exhaust of fluid to and from the smaller end of the piston, a trip rod normally adjoining the stem of 85 said last recited valve, and a trip carried by the piston and abutting in opposite directions on the trip rod in opposite directions of movement of the piston.

4. The combination of a fluid pressure 90 cylinder, a differential piston working therein, heads closing the ends of said cylinder, a valve chamber in the head adjoining the larger end of the piston, a fluid pressure supply pipe open continuously to the valve 95 chamber, supply and exhaust ports leading into the cylinder through the head, a valve normally seated, under supply pressure, in the pressure chamber, and controlling communication between said chamber and the 100 adjacent end of the cylinder and between said end and the exhaust port, means for unseating said valve, a valve chamber in the head adjoining the smaller end of the piston, a port connecting said chamber with 105 the supply pipe, supply and exhaust ports leading into the cylinder through said head, a valve normally seated in said pressure chamber and controlling communication between said chamber and the adjacent end of 110 the cylinder and between said end and the exhaust port, and a trip rod adjacent to the cylinder and actuated by the movement of the piston, for unseating said valve.

5. The combination of a fluid pressure 115 cylinder, a differential piston working therein, an automatically seating operating valve controlling the supply and exhaust of fluid to and from the larger end of the piston, means for unseating said operating 120 valve, an automatically seating valve controlling the supply and exhaust of fluid to and from the smaller end of the piston, and a trip rod adjacent to the cylinder and actuated by the movement of the piston, for unseating said last recited valve.

6. The combination of a fluid pressure cylinder, a differential piston working therein, an automatically seating operating valve controlling the supply and exhaust of 130

fluid to and from the larger end of the piston, means for unseating said operating valve, an adjustable regulating valve for varying the area for exhaust from the corresponding end of the cylinder, an automatically seating valve controlling the supply and exhaust of fluid to and from the smaller end of the piston, and a trip rod adjacent to the cylinder and actuated by the movement 10. of the piston, for unseating said last recited valve prior to the seating of the operating valve.

7. The combination of a fluid pressure cylinder, a differential piston working 15 therein, heads closing the ends of said cylinder, a valve chamber in the head adjoining the larger end of the piston, a fluid pressure supply pipe open continuously to the valve chamber, supply and exhaust ports leading 20 into the cylinder through the head, a valve normally seated, under supply pressure, in the valve chamber, and controlling communication between said chamber and the adjacent end of the cylinder, and between said

end and the exhaust port, mechanism for 25 unseating said valve, a valve chamber in the head adjoining the smaller end of the piston, a port connecting said chamber with the supply pipe, supply and exhaust ports leading into the cylinder through said head, 30 a valve normally seated in said valve chamber and controlling communication between said chamber and the adjacent end of the cylinder and between said end and the exhaust port, a trip rod bearing on the stem of 35 said last recited valve and fitted to reciprocate parallel with the piston, two longitudinally separated shoulders formed on said trip rod, and a trip fixed to the piston and adapted to abut against one or the other of 40 said shoulders in each direction of its movement, to unseat and permit the automatic seating, respectively, of said last recited valve.
